UNITED STATES PATENT OFFICE.

THOMAS S. GORTON, JR., OF EVANSTON, ILLINOIS.

NOVELTY BOX.

Application filed January 25, 1927. Serial No. 163,518.

This invention relates to a novelty box designed for the reception of loose articles, such as candy, etc. It incorporates into its structure certain unusual features which attract the eye, particularly of juvenile persons for whom the present box is especially intended.

It is a purpose of my invention to provide a box of the character described which may be formed of a single piece of board, appropriately configured and foldable into the desired shape; to provide connecting flaps by which the box is held together, dispensing if desired, with the aid of extraneous securing means; to utilize the box cover, or some other foldable part thereof, to simulate a well known and pleasing object which may be supported in an open or upright position to provide a novelty effect; and to accomplish the above ends in a manner which is simple, inexpensive and easily operated.

In the description to follow, as well as in the drawings to which reference will be made, the exemplification of my invention is in the form of a boat or raft of which the sail is the cover for the box. This is chosen as a convenient and apt illustration of one form which my invention may take, although obviously the box might be designed to simulate other objects which would prove interesting and attractive to the persons for whom it is intended.

Referring to the drawings, Figure 1 is a view in perspective of the box with the cover thereof folded down in closed position;

Fig. 2 is a plan view thereof;

Fig. 3 is a similar view with the cover open to simulate an erected sail upstanding from the deck of a boat;

Fig. 4 is a transverse section through the box with the cover thereof upstanding as in Fig. 3;

Fig. 5 is a view of the blank from which the box is formed;

Fig. 6 is a similar view of another blank for producing a modified form of box; and

Fig. 7 is a view in perspective of the box which is made up from the blank of Fig. 6.

Referring to Fig. 5, the blank therein shown comprises a central strip composed of integral sections arranged end to end and comprising a pair of adjacent sides A and B with end flaps C and D joined respectively thereto. Between the two side sections is a bend line *a* constituting the bow of the boat which is built up from this blank. The end

flaps C and D are connected to the side section A and B, respectively, along bend lines *b*.

Extending laterally from opposite sides of the side section A are flaps E and F connected thereto at bend lines *c*. A pair of similar flaps G and H extend oppositely from the other side section B, being connected thereto along a continuation of the same bend line *c*. Between the flaps E and F and the end flap C are other flaps I and J extending oppositely from the side section A and connected thereto along the same bend line *c*. These last named flaps are separated from the flaps E and F by severance lines *d* so as to be foldable independently thereof. The flap I is itself provided with a pair of bend lines *e* and *f*, the latter running in a direction which is parallel to the bend line *c* to define a tab 8 at its top. It is preferred that the bend line *e* be obliquely disposed, about as indicated, so that the area between itself and the bend lines *c* and *d* will constitute a deck portion 9 for the boat which is built up from this blank. In addition, one or more slots 10 are provided through the flap I in a direction perpendicular to the bend line *c* and preferably offset with each other as shown.

The flap J is provided on its edge opposite the side section A with a projecting tab 11, and also upon one side which is contiguous with the bend line *c* with a second projecting tab 12. The adjacent end flap C may likewise be provided at its end with a laterally projecting tab 13, a second tab 14 being extended from its opposite side as shown.

At the other end of the blank is a flap K extending from the side section B in the same direction as does the flap I from the corresponding edge of the side section A. An opening 15 of considerable size is formed in this flap, a portion of the material so cut therefrom being left intact to provide a leg 16 which may be folded upwardly along either of two bend lines *g* or *h* at its base where connection is made with the flap K. A tab 17 is extended laterally from the leg, as shown. From the edge of the side section B opposite the flap K is a tab 18, a slot 19 being formed adjacent the bend line *c* where it is joined to the section B. A second slot 20 parallel therewith is also formed in the side section centrally between its two bend lines *c* and close to the slot 19. I provide also in the end flap D a slot 21 which proceeds from the bend line *b* obliquely into the body of this flap.

With a blank so formed, it is possible to produce a novelty box of the kind which is shown in Figs. 1 to 4 inclusive. In arranging the components of the box, I execute a 5 bend at the line *a* which defines the bow of the boat. The two sections *E* and *F* are folded inwardly in parallelism and likewise the two sections *G* and *H*, the latter overlapping the others upon their outer sides. 10 The flap *J* is then bent around below the flap *H* to secure the latter in place, the tab 18 is upturned, and the tab 11 is entered in the slot 19 to secure the boat bottom *J* in place. The tab 12 is bent up to lie inside of the two 15 end flaps *C* and *D* which, when disposed in their intended positions, will lap past each other to form a back or stern for the boat. The hooked tab 13 may be entered through the slot 21 to secure the one flap to the other 20 although this method of fastening is optional. If desired, the one may be adhered to the other so as to ensure a permanent erected construction.

The upper structure of the novelty box 25 comprises the deck flap *K* which is brought to a horizontal position parallel with the bottom *J*, where it rests upon the overlapping flaps *G* and *H*. It is also rested upon the tab 14 which is bent inwardly from the end flap 30 *C*. The flap *I* which constitutes both the cover and sail is next brought to position. This is done by bending the deck portion 9 to overlie one edge of the deck flap *K*, and then upstanding the remainder of the flap to 35 simulate a hoisted sail. The leg 16 is next erected along either of the bend lines *g* or *h* so as to present its tab 17 to one of the two slots 10 wherein it may be locked. In the one position the sail is stood up from the deck 40 slightly higher than in the other with the deck portion 9 either horizontal or inclined according to which position is selected.

The leg 16 constitutes a support for the sail which, when erected, exposes the interior 45 of the novelty box. In this position articles may be placed in or taken from its interior through the opening 15. To close the box it is necessary merely that the sail support be folded down, following which the sail is also 50 folded down thereover to provide a closure for the box. When so disposed, its top tab 8 is bent along the line *f* to overlie the side section *B*, a portion of this tab being then 55 passed through the slot 20 where it serves to hold the cover fixedly in place. A lateral extension on the tab 8, simulating a flag or pennant, acts as a hook to lock the tab within the slot 20.

A box which differs in only minor particulars from the construction just described is set forth in Figs. 6 and 7. In this example the novelty of the article resides in its simulating the appearance of a raft rather than a boat having a pointed bow. The blank for 60 the raft construction comprises a bottom sec-

tion *J'* joined along its opposite edges by bend lines *i'* and *j'* to side sections *A'* and *B'*, respectively, in the latter of which is an elongated slot 20'. To the side section *A'* is joined along a bend line *k'*, a sail section *I'*, one portion 9' thereof which is defined by bend lines *k'* and *e'* providing an overlying deck portion. The top portion 8' of the sail may be appropriately configured to display a flag or other object having the mechanical function of serving as a tab for interlocking with the slot 20'. An underlying deck section *K'* which is joined to the side section *B'* along the bend line *l'* is provided with a cut-out 75 15' permitting access to the interior of the 80 box, and also providing a leg support 16' which is foldably connected to the deck section along one of the two bend lines *g'* or *h'*.

Joined to opposite ends of the bottom section *J'* are flaps *L'* and *M'* which, when 85 folded, lie to the inside of other flaps *N'* and *O'*, which are extended from opposite ends of the side section *A'* and also other flaps *P'* and *Q'* which are extended from opposite ends from the side section *B'*. When 90 folded into box relation, the flap *P'* is interlocked with the flap *N'* in the latter of which is a slit 22' for the reception of a hook 23' on the flap *P*. Similar slits and hooks are provided respectively in the flaps *O'* and *Q'* 95 whereby these also may be interlocked when the box is erected. This latter flap may also have a bend line *m'* to provide a tab 24' which is bent outwardly from one end, when the box is erected, to simulate a rudder for 100 the raft. The sail section *I'* may be upstood from the deck in the same manner as has already been described, the leg 16' sustaining it in this position. In like manner, when the leg support is folded down, the said section 105 may be closed over the deck section and be folded along the line *f'* to present its top tab 8' within the slot 20' whereby the box cover is secured in place.

The novelty package herein described may 110 conveniently be made of one piece of paper board. Its production involves but little expense, as does also its transportation on account of the flat condition in which it can be shipped. The bend lines are preferably 115 prearranged as by scoring the material at the proper places so as to facilitate the erection of the box. When filled with contents the cover may be closed down or may be left up with the leg support in sustaining position. The display thus afforded is attractive to the eye not only because of the unusual spectacular feature which is presented, but because the contents of the box are partially exposed. It is to be noted that the support 120 for the upstanding sail or other novelty feature is bendable from a horizontal to a vertical position but along a line which is angular, and preferably transverse, to the bend line of the sail. In this manner the 125 130

support is ample for all purposes. In addition, as already explained, the support may be adjusted to vary the angular position of the sail.

5 I claim:

1. A one-piece novelty box made up from a one piece blank having portions thereof adapted for interlocking to provide a bottom, sides, an apertured top, also a closure therefor which is both foldable down over the top or extensible vertically therefrom, a leg having its base connected to the top and swingable thereupon about an axis which is angular with respect to the folding axis of the closure, and adapted to lie thereunder when the closure is folded down, and means whereby the leg when erect may lock with the closure to hold the same in a vertical position, substantially as described.

20 2. A one-piece novelty box of the kind described in which is included an apertured top to which is connected a leg adapted to swing upwardly to a vertical position, and a closure

foldable over the leg about an axis which is angular with respect to the leg axis and 25 adapted either for disposal in a vertical direction or for overlying the apertured top and leg whereby to close the same, and means providing an adjustable connection between the closure and the leg such that the former 30 may be sustained by the latter in any one of a plurality of selected positions, substantially as described.

3. A one-piece novelty box which provides 35 an enclosure having an apertured top together with a folding closure therefor, means securing the closure to the box when in a position overlying the apertured top thereof, and other means for sustaining the closure in an elevated position with respect to the 40 top, said latter means forming part of the apertured top and being foldable into parallelism therewith, below the closure when the latter overlies the top, substantially as described.
